UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

WIRELESS RECEIVING CIRCUITS.

Application filed May 21, 1923, Serial No. 640,291, and in Great Britain May 31, 1922.

This invention relates to wireless receiving circuits of the type in which a crystal, such as carborundum requiring an auxiliary potential, is employed as the detector.

According to this invention a high resistance is employed in series with a cell or cells in place of the potentiometer which has hitherto been employed and the resistance and the cell are shunted by a condenser.

My invention is illustrated by the accompanying diagram of the connections in a crystal receiving set. The aerial circuit A is coupled to an oscillatory circuit O which is connected to a carborundum crystal C and a telephone T between which there are connected a high resistance R and a dry cell or cells B. The resistance may be, say, 100,000 ohms or more. K is a condenser shunting the resistance and cell for allowing high and low frequency oscillations to pass with low impedance.

This arrangement has the advantage that owing to the resistance the current from the cell is very small and therefore the life of the cell is considerably lengthened, and in addition to this it is found that practically all crystals of the same composition are in adjustment with the same resistance so that no adjustments are necessary when a new crystal is inserted.

Having described my invention what I claim is:—

1. A wireless receiving circuit comprising, an antenna circuit, a receiving circuit coupled thereto, a crystal detector associated with said receiving circuit, a resistance of the order of 100,000 ohms in series with said crystal detector, a battery connected in series with said resistance, said battery serving as a biasing means for said detector, a condenser adapted to pass both audio and radio frequency currents shunted around said resistance and battery, and means for receiving the detected signals from said receiving circuit.

2. A wireless receiving circuit comprising, an antenna circuit, a receiving circuit coupled thereto and adapted to be tuned to a desired frequency, a carborundum crystal detector associated with said receiving circuit, a resistance of the order of 100,000 ohms in series with said detector, a biasing battery for said detector connected serially with the opposite side of said resistance, a condenser adapted to by-pass both audio and radio frequencies shunted around said resistance and battery, and telephonic means for receiving the detected signal from said receiving circuit.

HENRY JOSEPH ROUND.
